(57) **CLAIM**

I claim the ornamental design for a cabinet for technical equipment, computer equipment and audio-visual equipment, as shown and described.

DESCRIPTION

FIG. 1 is a perspective view of a cabinet for technical equipment, computer equipment and audio-visual equipment showing my new design.

FIG. 2 is a front view of the cabinet shown in FIG. 1.

FIG. 3 is a right side view of the cabinet shown in FIG. 1.

FIG. 4 is a left side view of the cabinet shown in FIG. 1.

FIG. 5 is a rear view of the cabinet shown in FIG. 1.

FIG. 6 is a top view of the cabinet shown in FIG. 1.

FIG. 7 is a bottom view of the cabinet shown in FIG. 1.

FIG. 8 is a perspective view of a second embodiment of a cabinet for technical equipment, computer equipment and audio-visual equipment showing my new design.

FIG. 9 is a front view of the cabinet shown in FIG. 8.

FIG. 10 is a right side view of the cabinet shown in FIG. 8.

FIG. 11 is a left side view of the cabinet shown in FIG. 8.

FIG. 12 is a rear view of the cabinet shown in FIG. 8.

FIG. 13 is a top view of the cabinet shown in FIG. 8; and,

FIG. 14 is a bottom view of the cabinet shown in FIG. 8.

The portions of the cabinet shown in broken lines form no part of the claimed design.
